UNITED STATES PATENT OFFICE.

WALTER J. BARRON, OF BROOKLYN, NEW YORK, ASSIGNOR TO THE DENSMORE TYPEWRITER CO., OF SYRACUSE, NEW YORK.

TYPE-WRITING MACHINE.

SPECIFICATION forming part of Letters Patent No. 677,922, dated July 9, 1901.

Application filed May 12, 1900. Serial No. 8,292. (No model.)

To all whom it may concern:

Be it known that I, WALTER J. BARRON, a citizen of the United States, and a resident of the borough of Brooklyn, city of New York, in the county of Kings and State of New York, have invented certain new and useful Improvements in Type-Writing Machines, of which the following is a specification.

My invention relates to columnar or tabulating mechanisms, and has for its main object to provide a simple, convenient, and effective construction by which the operator may be assisted to quickly and positively locate the starting-point for a line of figures or other characters to form a column or a series of columns.

In the accompanying drawings, Figure 1 is a front elevation of the upper part of a Remington No. 6 type-writing machine containing my improvements. Fig. 2 is a side view thereof, partly in section and taken on the plane Y Y of Fig. 1. Fig. 3 is an enlarged perspective view looking from the rear side of part of the carriage release and stop mechanism. Fig. 4 is a vertical section taken at the line X X of Fig. 3. Fig. 5 is a perspective view to show more particularly a modified construction of stop on the carriage. Fig. 6 is a perspective view of a locking-dog forming part of the carriage-stop device. Fig. 7 is a perspective view of one of the detachable pointers or indicators. Fig. 8 is a perspective view looking from the rear and somewhat similar to Fig. 3, but showing my invention carried out in still another form and involving the use of a plurality of carriage-stops. Fig. 9 is a vertical section showing the manner of adjusting said stops, and Fig. 10 is a perspective view looking from the front side of certain devices shown in Fig. 8 and with one of the carriage column-stops in engagement with the frame-stop.

In the various views the same part will be found designated by the same numeral of reference.

Inasmuch as the general construction and mode of operation of the type-writing machine illustrated in the accompanying drawings are so well known, it will, perhaps, be unnecessary for me to describe all of the parts shown in the drawings, and I shall therefore

confine my description more particularly to the parts having relation to my improvements.

The paper-carriage in its entirety is designated by the numeral 1. At its front side 55 the carriage is provided with a roller 2, which travels on a track or way 3, which in this instance is the shift-rail of the machine, and at near its rear side the carriage is provided with other rolls 4, which travel on a rod 5, 60 supported on upwardly-extending ears on the top plate 6. Extending rearwardly from the center of the carriage is an arm 7, that is forked to straddle a sleeve 8, which slides upon a guide-rail 9, supported on posts 10, 65 rising from the top plate. The platen is designated by the numeral 11, and its shaft, as usual, is mounted to turn in side bars 12 of the carriage-frame, which latter is jointed or hinged at 13 to enable one portion of the carriage to be turned up for inspection of the work on the under side of the platen. 70

The carriage, as usual, is provided with a feed-rack 14, supported by arms 15 and meshing with a pinion 16, mounted at the inner 75 end of a shaft 17, that rotates in a bearing 18 on the top plate or framework, a rotary feed-rack or ratchet-wheel 19 and a backing-ratchet within a box 20 being provided at the rear end of said shaft, all in the usual manner. Coacting with said rack 19 are the usual feeding and detaining dogs 21 and 22, respectively mounted on a dog-holder (not shown) and arranged to be rocked back and forth at each operation of the key-levers. The carriage is connected by a strap 23 to a spring-drum 24, that tends to propel the carriage toward the left; but normally one or the other of the dogs 21 22 engages the rack-wheel, and through the shaft 17, pinion 16, and rack 14 80 85 the carriage is prevented from moving under the tension of the spring within the drum. When, however, a key is depressed, one dog moves out of the ratchet-wheel and the other in, and when the key is released the dogs resume their first positions, and either on the depression or the return of the key the carriage moves one letter-space, dependent upon whether the dogs are set to give the carriage the natural feed or the reverse feed. 90 95

The carriage may be released for rapid movements toward the left under the action

of the spring-drum independently of the escapement mechanism (consisting, primarily, of the dogs and the rack-wheel) by lifting the straight or longitudinally-arranged feed-rack 5 14 out of engagement with the pinion 16, the rack being attached to the arms 15, which are pivoted to the carriage, as usual.

The construction and operation thus far described are common to the machine illustrated 10 for embodiment of my invention, which latter may now be specifically described.

30 designates a side bar, which is perforated to take a bearing on the platen-axle 31; 32 another side bar, also perforated to take a 15 bearing on the platen-axle on the other or right-hand end of the platen, and 33 a front bar connected at its ends to the forward ends of said bars 30 and 32, the several bars forming a three-sided frame or bail, the bars 30 and 20 32 extending forward and backward transversely of the platen and the bar 33 being arranged in front of the platen-frame and extending from right to left longitudinally of the platen and for its entire length and the 25 frame or pivoted bail being mounted to embrace the platen on three sides. This frame may be made from one piece of metal; but preferably I make the several bars of separate parts and form the end bars with ears or 30 lugs and screw them to the front bar, as indicated at 33^x in Figs. 3 and 8.

The rear ends of the bars or arms 30 are extended back far enough to engage with projections 35 on the rack 14 (or on the arms 15) 35 in a manner such that when the pivoted bail or frame is rocked, as by the depression of the bar 33, the inner ends of the arms 30 will rise and lift the feed-rack out of mesh with the pinion 16, and thus release the carriage 40 for rapid movement toward the left. The bar 33, extending for the full length of the platen, may be depressed for disengaging the carriage by pressing down upon it at any portion of its length, thus providing a convenient 45 carriage-release-key mechanism, the bar 33 constituting, in effect, an elongated key, so far as the releasing function of the mechanism is concerned. This capacity of the mechanism to release the carriage by pressure 50 upon the bar or key 33 at any point is especially useful or advantageous in connection with column-stop devices, such as will now be described, referring more particularly at this time to Figs. 1 to 7, inclusive.

55 Mounted upon the bar 33 is a column-stop device, designated as a whole by the numeral 36, comprising, in the example shown, a slide, frame, box, or collar adapted to be moved endwise on said bar, the device shown consisting of a front plate 37, having on each end upper and lower hooks 38, which are bent over and around the upper and lower edges of the bar 33, so as to embrace the same, and also of a rearwardly-projecting horizontal lug 60 65 or ear 39, through a perforation in which passes the vertical stem 40 of a key-piece, the lower end of the stem being threaded to

engage with a tapped hole in a dog or ratchet-piece 41 and the upper end of the stem being provided with a button or finger-piece 70 42, between which and the top of the plate 39 is arranged a coiled spring 43 for keeping the dog or detent device 41 and its attached key normally in a raised position.

Extending along the bar 33 and below the 75 detent 41 is a rack-bar 44 to engage the detent when the latter is depressed and for the purpose of locking the slide or sleeve 36 in its adjusted position. The slide carries a depending arm 45, which is provided at its lower 80 free end with a dog or stop member 46, which at certain times is adapted to contact with a fixed stop or projection 47, arranged on the framework or some part mounted therein. In this case the stop 47 is on an arm 48 and 85 secured to the shift-rail 3 and is the same arm that is now provided in the Remington machine with an index or pointer to coöperate with the platen-scale.

A spring 50, coiled around the platen-shaft 90 and bearing at its forward end against a projection 51 on the release-frame and at its rear end against a portion of the carriage, tends to keep the release-key frame in a raised position and the projection 46, carried thereby, 95 in a horizontal plane above that of the frame-stop 47, so that during the course of ordinary work these two stop members will not come into engagement. When, however, the bar 33 is depressed against the tension of said 100 spring, (and there may be one such spring at each end of the frame,) the stop 46 is carried down into the horizontal plane of the relatively-fixed stop 47, and when the former reaches the latter during the leftward movement of the carriage a contact of the stops is effected, and the carriage is automatically arrested and held against travel to the left as long as the bar 33 is held down. When the bar is released, the stop 46 rises above 105 the top of the stop 47 and the carriage may travel farther toward the left. On the return motion of the carriage the stop 46 will pass over the stop 47, assuming that the vibratory stop-frame is in its normal raised 115 position. From what has already been said it will be understood, of course, that when the bar 33 is depressed to bring the stops 46 47 into coöperative relationship the carriage is freed, or "detached," so to speak, from its 120 escapement mechanism by a separation of the rack and pinion 14 and 16, and hence the carriage is at liberty to travel freely toward the left by the power of the mainspring.

In the construction of adjustable stop 125 shown in the main views it will be observed that the device is adapted to be slid freely along the bar or support 33, and hence to be brought quickly to any desired point thereon, after which it may be locked in its new 130 or adjusted position by the engagement of the dog or ratchet with the rack-bar, and thus be held securely against displacement at the time the stops 46 47 strike or engage each

other. In operation the user will find it convenient to grasp the device so that the index-finger rests upon the top of the key or button 42 and then after moving the contrivance to 5 the desired locality to press down upon said button to cause the ratchet devices to interlock and by continued pressure either upon said button or by other fingers upon the edge of the bar or key 33 to cause the frame as a 10 whole to descend and the stop 46 to be brought into position to engage the stop 47 upon its subsequent arrival at the place where said stop is located, which is preferably in a vertical plane passing transversely through 15 the platen and the printing-point.

In adjusting the slide or stop device along the bar 33 a scale or scales or other indicating devices may be employed to assist the user to arrive quickly at any desired point or 20 points. For example, the stop 46 may be shaped, as in the case shown, to act as a pointer and to lie in proximity to the carriage-scale 49, whereby said scale may be utilized for an adjustment by said stop. Thus if it 25 be desired to release the carriage and have it run rapidly toward the left and be stopped by the contact of stops 46 and 47 at, say, "60" on the scale the device 36 is slid in the proper direction until the stop or pointer 46 registers 30 or aligns with "60" upon the scale. Then the button is depressed and the stop locked to the bar, and the whole frame is depressed and the carriage released to travel unrestrainedly toward the left. When the stop 46 35 strikes the stop 47, the carriage will be arrested at a point corresponding to "60" on the scale. The bar may then be released and the carriage reengaged with the escapement mechanism and put in condition for further 40 travel step by step toward the left.

Glancing at Fig. 1, it will be seen that the right-hand side of the stop 47 serves also as a pointer and by reference to the scale 49 that the carriage has traveled twenty-two letter-spaces toward the left. It will also be observed that the column-stop has been moved or adjusted to the point "60" on said scale. If now the button 42 and the bar 33 be depressed, the stop will be locked, the carriage 45 released, and the stop 46 will travel with the carriage until it strikes the stop 47, as before explained.

While I have shown a double-toothed dog or detent 41, a single dog only may be employed, and instead of having the dog slide to and from the rack 44 it may be mounted upon an arm pivoted to the slide, so as to have a swinging or vibratory movement. Indeed a variety of forms of detents, catches, 50 or locking devices may be employed for holding the normally free-to-slide stop device in its adjusted or desired working position in place of the construction shown.

As shown at Fig. 5, the plate 37 may be cut 55 away and formed or provided with a pointer or index 52 to coöperate with a scale 53, formed

on the face of the bar 33, to facilitate the adjustments of the stop.

As a further aid to the user, especially where a piece of work is being written involving a 70 plurality of columns, a series of detachable clips 54 may be employed and arranged at the different points along the scale-bar 49 at which the various columns are to commence. For example, as shown at Fig. 1, these pointers or indexes are arranged at "4," "23," "44," and "64," the remaining three therein shown being in positions of disuse. In adjusting the column-stop 46 it may be found more convenient or speedy for some operators to effect registration between the stop and the fingers than between the stop and the 75 graduations on the scale; but, aside from this, the placement of the fingers at the points where the various columns are to begin relieves the operator from memorizing these various points or of referring to the paper being written or to side notes or memoranda or to specially-prepared paper-scales. 80

The indexes 54 are preferably formed of 90 sheet metal, generally of U shape or formed to straddle over or embrace the scale-bar, and pointed or sharpened at their lower ends to more exactly register with the lines or graduations on the scale. These indices 54 may 95 be slid along the scale and grouped at either or both ends thereof when not desired for use; but they preferably have enough friction or grip to hold them in their adjusted positions. At the same time it will be seen that 100 they may be readily detached from the bar when not wanted for use.

The depressible column-stop frame may be provided with a lateral finger-piece 55, which may serve in place of the usually-employed 105 carriage-release key located at a similar place in the Remington No. 6 machine in order not to interfere with the custom of an operator familiar with this machine when it may be desired to release the carriage for a purpose 110 other than tabular work, it being understood that in this machine the usual release-key is preferably omitted and that the device 37 will not interfere with the free movement of the carriage when the finger-piece 55 is operated, so long as the dog 41 remains out of engagement with the rack 44. 115

Referring to Figs. 8, 9, and 10, the depressible carriage-release and column-stop frame is provided with a plurality of adjustable stops; 120 but these, unlike the single stop shown in the other views, are normally not free to be slid or adjusted along said bar, but, on the contrary, are normally engaged therewith. In this construction the stops are intended to be 125 set in the proper positions for a predetermined piece of work or a plurality of columns, and accordingly the stops are constructed differently from the stop first above described. Each stop comprises a plate or bar portion, 130 as 37^a, having a hook at its upper end which embraces the upper edge of the bar 33^a, and

a tooth or dog 33^b on its lower end which normally engages a tooth-space formed by a rack 33^c on the lower edge of the bar 33. The plate 37^a is provided on its inner face with a hook-shaped plate-spring 56, whose point engages the inner face of the bar 33^a and holds the stop device firmly in position thereon. The manner of adjusting the stop upon the bar is illustrated at Fig. 9. The lower end of each plate 37^a constitutes a stop, as 46^a, which is adapted to coöperate with the fixed stop 47 when the frame has been depressed and the carriage released in the manner hereinabove described with reference to other views.

15 The adjustment of a power-driven paper-carriage by means of the ordinary release-key is attended with some difficulties, because the weight of the carriage, combined with the driving-spring tension thereon, renders the carriage likely when put in rapid motion to move beyond the desired point, and in attempting to return the carriage to the desired point there is likelihood of moving it back too far, so that owing to this vibration 20 back and forth about the point at which it is desired to arrest the carriage undue time is consumed. For this reason it is customary with some operators to bring the carriage rapidly to a point near the desired point and 25 then to feed it along to the right place by one or two taps upon the space-key. One of the principal objects of my invention is to avoid these difficulties and expedite the positioning of the carriage. To this end it will be seen 30 that the device 37 may be not only slid rapidly along the bar 33, but may be instantly arrested at any point determined by reference to the scale 49, and then the key which is mounted upon said device 37 may be depressed, so that the carriage is released and 35 may be moved rapidly until arrested by the stop 47, the whole operation requiring much less time and mental labor than usual in positioning the carriage.

40 45 Inasmuch as several features of my invention may be carried out in other ways, I do not limit the invention to the precise details of construction and arrangement herein set forth.

50 55 What I claim as new, and desire to secure by Letters Patent, is—

1. In a type-writing machine, the combination of a power-driven paper-carriage, escapement devices therefor, and a bail pivotally mounted by its arms upon said carriage connected to said escapement devices, said bail comprising a part which unites said arms and is arranged in front of the platen and extends the entire length thereof, a columnar stop on said part which unites said arms, and a coacting stop mounted on the frame.

60 65 2. In a type-writing machine, the combination with a platen-frame and a platen journaled therein, of a bail whose arms are pivoted upon said platen-journals, said bail comprising a bar arranged in front of said platen-frame and extending parallel with said

70 platen, and at least one of said side arms being operatively connected to release said carriage to permit its rapid movement.

3. In a type-writing machine, the combination with a carriage and escapement mechanism therefor, of a release-key comprising a U-shaped frame having side arms pivoted at the ends of the carriage, and a long bar arranged 75 at the front of the carriage and extending longitudinally thereof for substantially the entire length of said carriage, a stop on said bar, and a coacting stop arranged upon the framing, one of said stops being adjustable 80 in a line parallel with the carriage travel, and the stop on the framing being out of the normal path of the stop on said bar.

4. In a type-writing machine, the combination with a carriage and escapement devices 85 therefor, of a release-key arranged upon the forward part of said carriage and extending longitudinally thereof, a stop adjustable along said release-key, and a relatively-fixed stop, the latter being out of the normal path of the 90 release-key stop, the construction and arrangement being such that upon the operation of said release-key to release the carriage from the control of its escapement devices, the said release-key stop is projected to a 95 position in which it may engage said relatively-fixed stop to arrest the carriage at a position corresponding to the adjustment of said release-key stop.

5. In a type-writing machine, the combination 100 with a carriage and escapement devices therefor, of a release-key arranged upon the front part of said carriage and extending longitudinally thereof, a rack provided upon said release-key, a stop adjustable along said release-key and provided with means for engaging said rack, and a relatively-fixed coacting stop arranged out of the normal path 105 of said adjustable stop, the construction and arrangement being such that upon depression 110 of said release-key to effect the release of the carriage, said adjustable stop is projected to a position to engage said relatively-fixed stop to cause the arrest of the carriage at a point determined by the adjustment of said adjustable stop.

6. In a type-writing machine, the combination 115 with a carriage and escapement devices therefor, of a bail pivoted by its arms upon said carriage and operatively connected to 120 said escapement devices so as to release the carriage from their control, said bail comprising a key arranged forwardly of said escapement devices and extending for substantially the entire length of the carriage, a stop adjustable along said key, and a coacting relatively-fixed stop arranged out of the normal 125 path of said adjustable stop and constructed to arrest the latter, together with the carriage, upon the carriage being released by the operation of said release-key.

7. In a type-writing machine, the combination 130 with a carriage and escapement devices therefor, of a bail pivoted upon the carriage

for releasing the latter from the control of said escapement devices, said bail comprising a key arranged forwardly of the carriage and extending for substantially the entire length 5 thereof, a rack provided upon said key, an adjustable stop upon said key provided with means for engaging said rack, and a relatively-fixed stop arranged out of the normal path of said adjustable stop and constructed 10 to arrest the latter, together with the carriage, upon the release of the carriage by said release-key.

8. In a type-writing machine, the combination with a carriage and escapement mechanism therefor, of a depressible release-key connected to disengage said carriage from the control of said escapement mechanism, said depressible key extending for substantially the whole length of said carriage and parallel 20 therewith and upon the forward portion thereof, a stop adjustable along said depressible key, and a relatively-fixed stop arranged below the normal path of said adjustable stop.

9. In a type-writing machine, the combination with a carriage and an escapement mechanism therefor, of a depressible release-key arranged upon the forward part of said carriage and extending for substantially the entire length thereof, a rack upon said release-key, a stop adjustable along said release-key and provided with means for engaging said rack, and a relatively-fixed stop constructed to coact with said adjustable stop but arranged out of the normal path of the latter.

35 10. In a type-writing machine, the combination with a carriage, an escapement mechanism therefor, a scale mounted upon said carriage, and a relatively-fixed index, of a release-key arranged upon the carriage parallel with said scale and extending for the entire length thereof, and a column-stop adjustable along said release-key and provided with an index for coöperation with said scale, whereby said column-stop may be adjusted 40 so as to arrest the carriage at the desired position after release.

11. In a type-writing machine, the combination with a carriage and escapement devices therefor, of a scale arranged upon the 50 front of said carriage, a relatively-fixed index constructed to coöperate with said scale and also to serve as a stop, and a column-stop adjustable along said scale and constructed to be projected at will into a position to engage said index or fixed stop.

12. In a type-writing machine, the combination with a carriage and an escapement mechanism therefor, of a release-key mounted upon said carriage and extending for substantially the entire length thereof, a rack 60 provided upon said release-key, a stop adjustable along said key but normally disengaged from said rack, and means for engaging said stop at will to said rack.

65 13. In a type-writing machine, the combination with a carriage and an escapement mechanism therefor, of a release-key mounted

thereon and extending for substantially the entire length thereof, a rack provided upon said release-key, a stop adjustable along said key but normally disengaged from said rack, means for engaging said stop at will to said rack and simultaneously operating said release-key, and a relatively-fixed stop for coaction with said adjustable stop.

75 14. In a type-writing machine, the combination with a carriage and an escapement mechanism therefor, of a release-bar extending parallel with the carriage and provided with a rack, a slide adjustable along said bar, 80 a key-piece mounted upon said slide, a dog operatively connected to said key-piece but normally disengaged from said rack, whereby said slide may be moved freely over said bar and said key-piece may be operated to engage 85 said slide with said rack at any desired point, whereupon said bar may be operated to release the carriage from the control of its spacing mechanism, and a relatively-fixed stop constructed to engage with said adjustable stop to arrest the carriage.

90 15. In a type-writing machine, the combination with a carriage and an escapement mechanism therefor, of a longitudinally-extending release-bar, a slide thereon, a vertical stem mounted on said slide and provided with a key, a dog attached to said vertical stem, a spring for holding said dog out of engagement with said rack, and a relatively-fixed stop.

100 16. In a type-writing machine, the combination with a carriage and an escapement mechanism therefor, of a key or finger-piece, as 42, adjustable along said carriage, and means controlled by said key or finger-piece 105 for releasing said carriage at any point and for arresting said carriage at a point determined by the adjustment of said key or finger-piece.

110 17. In a type-writing machine, the combination with a carriage and an escapement mechanism therefor, of a device mounted upon the front of the carriage and movable in one direction for predetermining the position at which the carriage shall be arrested, 115 and movable in another direction for subsequently effecting the release of the carriage.

120 18. In a type-writing machine, the combination with a carriage and an escapement mechanism therefor, of a device which normally is free to be moved in either direction parallel with the travel of the carriage, for predetermining at what point the carriage shall be arrested, and which is movable in another direction for subsequently releasing the 125 carriage from the control of said escapement mechanism.

130 19. In a type-writing machine, the combination with a carriage and an escapement mechanism therefor, of a device which is mounted on said carriage and normally movable freely in either direction parallel with said carriage, to predetermine the position at which the carriage shall be arrested, and

which may be moved in a crosswise direction for temporarily locking it in its adjusted position and simultaneously releasing said carriage from the control of its escapement devices.

20. In a type-writing machine, the combination with a carriage and an escapement mechanism therefor, of a bail pivotally mounted by its arms upon said carriage and connected to said escapement mechanism so as to release the carriage from the control thereof, said bail comprising a bar or key extending parallel with the carriage and for substantially the entire length thereof, a stop adjustable along said bar or key, a relatively-fixed stop arranged below the normal path of said adjustable stop, and a spring upon said carriage for keeping the said key or bar in a raised position.
21. In a type-writing machine and in a column-stop mechanism, the combination with a carriage, its escapement mechanism and a depressible release-key mechanism provided with an adjustable stop, of a scale provided

with one or more adjustable indices adapted 25 to facilitate the adjustment of the stop on the release-key, and a relatively-fixed stop for coöperating with said adjustable stop.

22. In a type-writing machine, the combination with a carriage, an escapement mechanism therefor, and a scale arranged upon the front of said carriage, of a series of indexes adjustable along said scale, a release-key arranged above said scale and parallel therewith, and a carriage-stop adjustable along 35 said release-key and provided with an index for coöperation with said series of indexes to determine the position to which said stops shall be adjusted.

Signed at the borough of Manhattan, city 40 of New York, in the county of New York and State of New York, this 8th day of March, A. D. 1900.

WALTER J. BARRON.
